SHEET REGISTERING MECHANISM FOR SHEET FED PRINTING PRESSES

Hans J. Luehrs, Westerly, R. I., assignor to The Cottrell Company, Westerly, R. I., a corporation of Delaware

Application May 10, 1955, Serial No. 507,331

16 Claims. (Cl. 271—48)

My invention is directed to improvements in sheet registering mechanism for sheet fed printing presses, and particularly to novel means for side registering and guiding the sheets.

One object of my invention is to provide a novel side guide which includes a reciprocating gripper and a stationary side stop located between the coacting sheet gripping members, and particularly between the sheet gripping surfaces of the said gripping members; the gripper being operable to pull a temporarily arrested sheet laterally into contact with the side stop, with a positive, quick action without marking, crushing or otherwise distorting the sheet.

Another object is to provide means for adjusting the pressure exerted by the gripper members on the interposed sheet.

Another object is to provide means for causing the gripper members to exert a powerful bite on the sheet while the sheet is being pulled laterally into register with the stationary side stop, and yet positively confine the side registered sheet as the gripper completes its side registering movement in frictional contact with the sheet.

Another object is to provide means for changing the dwell of the gripper bite on the sheet being side registered.

Another object is to provide novel means for reciprocating the gripper and for actuating the gripper members.

Another object is to provide a reciprocating gripper which is not only positive in its action but requires no sensitive nor fine setting or adjustment for its proper functioning.

Another object is to provide a side stop which is thinner than the thickness of the sheet being treated, to allow the sheet to be firmly grasped by the gripper without contacting the side stop.

A practical embodiment of my invention is represented in the accompanying drawings, in which:

Fig. 1 represents a diagrammatic side elevation of a multi-color rotary printing press and its sheet feeding and delivery mechanisms;

Fig. 2 represents a detail top plan view showing two oppositely positioned duplicate side guides with a sheet located between their reciprocating gripper members, the sheet being shown as pulled laterally into contact with the side stop of one of the said side guides;

Fig. 3 represents a side view, partly broken away, of the side guide and its adjacent elements, showing the front sheet stop which end registers and temporarily arrests the sheet, and also the pinch rolls for feeding the end and side registered sheets to the printing press;

Fig. 4 represents an end view of the side guide and its adjacent elements;

Fig. 5 represents a considerably enlarged vertical section taken in the planes of the line V—V of Fig. 3;

Fig. 6 represents a detail vertical section, on an enlarged scale, taken in the plane of the line VI—VI of Fig. 4;

Fig. 7 represents a detail vertical section, on an en-

2

larged scale, taken in the plane of the line VII—VII of Fig. 4;

Fig. 8 represents a detail view, in side elevation on an enlarged scale, of the reciprocating sheet gripper of the side guide with the sheet in contact with the stationary side sheet stop, and

Fig. 9 represents a top plan view of the same.

The sheet fed rotary printing press which I have chosen to show in connection with the new side guide, is denoted by 1. The sheet feeding means is shown as including the usual endless carrier 2 and the feed board 3.

The front sheet stop for end registering the sheets, is denoted by 4 and it may be operated by any well known or approved means (not shown herein) for temporarily arresting the sheets while they are being side registered.

Means, as coacting pinch rollers 5 and 6, are shown for forwarding the sheets to the printing press after they have been both end and side registered.

The endless carrier 7 may be used for delivering the printed sheets from the printing press to a predetermined point or points.

The main press frame is denoted by 8 and the laterally adjustable auxiliary frame which forms part of the side guide unit is denoted by 9.

As the side guides are alike, one only will be specifically described herein. The side guide is shown as including a stationary side sheet stop 10 which may be a strip of suitable material, as steel, of the required thickness. The side guide also includes a reciprocating gripper having upper and lower members 11 and 12 with their sheet gripping pads 13 and 14, between which gripper members the sheets are fed one at a time along the feed board 3. It will be noted that the side sheet stop 10 is slightly thinner than the sheet being handled so that the sheet stop will not interfere with the coacting surfaces of the gripper members as they complete their outward sliding movement.

The upper gripper member 11 is hinged to a lug 15 uprising from the lower gripper member 12, preferably by means of an eccentric pivot pin 16.

The lower member 12 is shown as slidable in a groove 17 in the top of the auxiliary frame 9, the gripper surface of lower pad 14 being flush with the top of the feed board 3 to permit the unrestricted passage of the sheet into and out of the said gripper surfaces when the gripper is opened. The ends of the side stop 10 may be secured to the top of the auxiliary frame 9 in line with the feed board 3 at both sides of the gripper by the bolts 10* and clamping blocks 10**.

The gripper pad 13 of the upper gripper member 11 is arranged to coact with the gripper pad 14 of the lower gripper member to grasp the sheet with a predetermined pressure when the gripper is closed, sufficient to pull the sheet laterally into register with the stationary side stop 10. These coacting gripper surfaces of the gripper members are of considerable area so as to provide an extended contact with the said sheet.

The means which I have shown for reciprocating the gripper is shown as including the following elements:

A cam shaft 18 is rotatably mounted in the auxiliary frame 9 and a box cam 19 is keyed on said shaft. The groove 20 of this cam receives the roller 21 which is carried by an arm 22 depending from the lower gripper member 12.

The means which I have shown for opening and closing the gripper members is as follows:

A pair of coacting cams 23, 24 are mounted on the cam shaft 18, one of which cams is rotatably adjustable with respect to the other cam by the bolts 25 and grooves 26. A cam roller 27 which engages said cams is carried by a rock lever 28 pivoted at 29 on the auxiliary frame 9.

This rock lever 28 is provided with an element 30 which contacts the bottom end of a vertically disposed spring pressed plunger 31, which is slidably mounted in a housing 32 of the auxiliary frame 9 and an elongated slot 33 of the lower sliding member 12. The coil spring 34 surrounds the plunger 31 within the housing 32 for yieldingly pressing the plunger onto the contact element 30 to keep the roller 27 in contact with its cams 23, 24.

A roller 35 is carried by the lugs 36, which depend from the upper gripper member 11, which roller travels back and forth along the flat top of the plunger 31, as the gripper reciprocates.

The means tending to close the gripper members with a predetermined pressure, is shown as a vertically adjustable rod 37 having its lower end screwed into a lug 38 uprising from the lower gripper member 12. This rod 37 extends upwardly through the upper gripper member 11. A coil spring 39 is located around the rod 37 between the adjustable knob 40 of said rod and the upper gripper member 11.

More or less pressure may be applied to the upper gripper member by means of the adjustable knob 40.

The means which I have shown for adjusting the auxiliary frame 9 laterally in the main frame 8 to properly position the said guide for sheets of different widths, is as follows:

The auxiliary frame 9 has an interlocking sliding engagement with the main frame 8 as by providing the main frame with a pair of undercut tracks 42, 42 for receiving the pair of projecting bottom slides 43, 43 of the auxiliary frame. A cross bolt 44 is threaded through the pair of uprising arms 45, 45 of the bracket 46. A pair of bolts 47, 47 are fixedly mounted in the auxiliary frame 9, and pass through and are secured to the uprising arms 45, 45 of the bracket 46.

A suitable tool (not shown) may be used to removably engage the angular end 48 of the cross bar 44 for turning it to adjust the auxiliary frame to the required position.

The means which I have shown for locking the auxiliary frame in this adjusted position comprises the hand lever 49 threaded on one of the bolts 47 and connected by a rod 50 to an arm 51 threaded on the corresponding end of the other bolt 47. The rocking of this lever 49 serves to clamp slides 43, 43 of the auxiliary frame to the tracks 42, 42 of the main frame 8.

In the present instance the sheets are shown as being fed in overlapping relationship, the end and side registered sheet *a* being shown as being fed to the press, the temporarily arrested end registered sheet *b* as being located in the side guides and the sheet *c* as approaching the side guides.

In operation, each side guide is brought into its proper position for the width of sheet being registered, by the lateral adjustment of its auxiliary frame, which frame is then locked in such position. The reciprocating gripper of one side guide has its sheet embracing members grasping the sheet with sufficient pressure to pull the sheet laterally into register with its stationary side stop 10, while the sheet embracing members of the opposite side guide are caused to contact the sheet with a lesser pressure to exert resistance on the sheet to keep the sheet even. After the sheet has been side registered, the pressure on the sheet is reduced until the gripper completes its stroke and then released to permit the side registered sheet to be advanced to the press by the pinch rolls 5 and 6 as soon as the front stop 4 is withdrawn.

If the other side guide is to be used to side register the sheet, the differential pressure exerted by the two grippers are reversed.

In some instances, where heavy sheets are to be treated, a combined push and pull effect on the sheet is accomplished by causing the gripper members of both side guides to exert the desired high pressures on the sheet. In this case the cam 19 for the gripper is 180° displaced so both grippers work in one direction instead of in opposite directions.

In some instances also the sheet may be side registered by the use of only one of the side guides. It will be noted that by providing a side stop of lesser thickness than the sheet being treated, the stop may be placed between the gripping surfaces of the gripper members without being contacted by the members when high pressure is applied on the sheet. This positioning of the side stop also causes it to assist the gripper members in positively confining the sheet successfully.

It is evident that various changes may be made in the construction, form and arrangement of the several elements without departing from the spirit and scope of my invention, and hence it is not intended to be limited to the particular embodiments shown and described herein.

What I claim is:

1. In a sheet registering mechanism for sheet fed printing presses, a sheet confining side guide including a reciprocating side gripper having upper and lower sheet embracing gripper members with coacting sheet gripping surfaces, and a stationary side stop located permanently between the said coacting sheet gripping surfaces, and means for causing the gripper members to grasp the sheet and pull it laterally with a predetermined pressure into register with said side stop.

2. In a sheet registering mechanism for sheet fed printing presses, a sheet confining side guide including a reciprocating side gripper having upper and lower sheet embracing members with coacting sheet gripping surfaces, and a stationary side stop located permanently between the said coacting sheet gripping surfaces, and means for causing the gripper members to grasp the sheet and pull it laterally with a predetermined pressure into register with said side stop.

3. In a sheet registering mechanism for sheet fed printing presses, a sheet confining side guide including a reciprocating side gripper having upper and lower sheet embracing members with coacting sheet gripping surfaces, and a stationary side stop located permanently between the said coacting sheet gripping surfaces, and means for causing the gripper members to grasp the sheet and pull it laterally with a predetermined pressure into register with said side stop before the gripper members reach the limit of their stroke and to remain in frictional contact with the sheet during the remainder of said stroke.

4. In a sheet registering mechanism for sheet fed printing presses, a sheet confining side guide including a reciprocating side gripper having upper and lower sheet embracing members with coacting sheet gripping surfaces, and a stationary side stop located permanently between the said coacting sheet gripping surfaces, means for causing the gripper members to grasp the sheet and pull it laterally with a predetermined pressure into register with said side stop before the gripper members reach the limit of their stroke and to remain in frictional contact with the sheet during the remainder of said stroke, said side stop being thinner than the sheet being handled.

5. In a sheet registering mechanism for sheet fed printing presses, a sheet confining side guide including a reciprocating side gripper having upper and lower sheet embracing members with coacting sheet gripping surfaces, and a stationary side stop located permanently between the said coacting sheet gripping surfaces, means for causing the gripper members to grasp the sheet and pull it laterally with a predetermined pressure into register with said side stop, and means for changing the dwell of the gripper bite on the sheet.

6. In a sheet registering mechanism for sheet fed printing presses, a sheet confining side guide including a reciprocating side gripper having upper and lower sheet embracing members with coacting sheet gripping surfaces, and a stationary side stop located between the said coacting sheet gripping surfaces, means for causing the gripper members to grasp the sheet and pull it laterally with a predetermined pressure into register with said side stop, and means for adjusting the side guide laterally to handle sheets of different widths.

7. In a sheet registering mechanism for sheet fed printing presses, a sheet confining side guide including a reciprocating side gripper having upper and lower sheet embracing members with coacting sheet gripping surfaces, and a stationary side stop located permanently between the said coacting sheet gripping surfaces, means for causing the gripper members to grasp the sheet and pull it laterally

with a predetermined pressure into register with said side stop, means for adjusting the side guide laterally to handle sheets of different widths, and means for locking the side guide in its adjusted position.

7. In a sheet registering mechanism for sheet fed printing presses, a pair of oppositely disposed sheet confining side guides, each side guide including a reciprocating side gripper having sheet embracing members and a stationary side stop located permanently between the gripper members, means for causing the gripper members of one side guide to grasp the sheet and pull it laterally in one direction with a predetermined pressure into register with its side stop, and means for causing the gripper members of the opposite side guide to travel in the opposite direction and to frictionally engage the sheet with a lesser pressure to exert a restraining effect on the said sheet.

8. In a sheet registering mechanism for sheet fed printing presses, a pair of oppositely disposed sheet confining side guides, each side guide including a reciprocating side gripper having sheet embracing members and a stationary side stop located permanently between the said gripper members, means for causing the gripper members of one side guide to grasp the sheet and pull it laterally in one direction with a predetermined pressure into register with its side stop, and means for causing the gripper members of the opposite side guide to travel in the same direction and to grasp the sheet with a predetermined pressure to exert a pushing effect thereon in the same direction.

9. In a sheet registering mechanism for sheet fed printing presses, a sheet confining side guide including a reciprocating side gripper having upper and lower sheet embracing members with coacting sheet gripping surfaces, a stationary side stop located permanently between the said sheet gripping surfaces and cam operated devices for causing the gripper members to grasp the sheet with a predetermined pressure and pull it laterally into register with said side stop.

10. In a sheet registering mechanism for sheet fed printing presses, a sheet confining side guide including a reciprocating side gripper having sheet embracing members with coacting sheet gripping surfaces, a stationary side stop located permanently between the sheet gripping surfaces, a rotary cam means and devices operated thereby for causing the gripper members to grasp the sheet with a predetermined pressure and to pull it into register with said side stop.

11. In a sheet registering mechanism for sheet fed printing presses, a sheet confining side guide including a reciprocating side gripper having sheet embracing members with coacting sheet gripping surfaces, a stationary side stop located permanently between the sheet gripping surfaces, a rotary cam means and devices operated thereby for causing the gripper members to grasp the sheet with a predetermined pressure and to pull it into register with said side stop, said rotary cam means being adjustable to change the dwell of the gripper bite on said sheet.

12. In a sheet registering mechanism for sheet fed printing presses, sheet feeding means, a front stop for end registering and temporarily arresting the fed-in sheet, and a side guide including a reciprocating side gripper having upper and lower sheet embracing members with coacting gripping surfaces, a stationary side stop located permanently between the gripping surfaces and means for causing the gripper members to grasp the temporarily arrested sheet with a predetermined pressure and pull it laterally into register with the side stop.

13. In a sheet registering mechanism for sheet fed printing presses, a main frame, sheet feeding means, a front stop for end registering and temporarily arresting the fed-in sheet, an auxiliary frame and a side guide carried thereby and including a reciprocating side gripper having upper and lower sheet embracing members with coacting gripping surfaces, a stationary side stop located permanently between the said gripping surfaces, and means for causing the gripper members to grasp the temporarily arrested sheet with a predetermined pressure and pull it laterally into register with the side stop.

14. In a sheet registering mechanism for sheet fed printing presses, sheet feeding means, a front stop for end registering and temporarily arresting the fed-in sheet, a side guide including a reciprocating side gripper having upper and lower sheet embracing members with coacting sheet gripping surfaces and a stationary side stop located permanently between the sheet gripping surfaces of said gripper members, and means for causing the gripper members to grasp the temporarily arrested sheet with a predetermined pressure and pull it laterally into register with the side stop before the gripper members reach the end of their stroke and to remain in frictional contact with the sheet during the remainder of the stroke of the said gripper members.

15. In a sheet registering mechanism for sheet fed printing presses, sheet feeding means, a front stop for end registering and temporarily arresting the fed-in sheet, a side guide including a reciprocating side gripper having upper and lower sheet embracing members with coacting sheet gripping surfaces and a stationary side stop located permanently between the sheet gripping surfaces of said gripper members, means for causing the gripper members to grasp the temporarily arrested sheet with a predetermined pressure and pull it laterally into register with the side stop before the gripper members reach the end of their stroke and to remain in frictional contact with the sheet during the remainder of the stroke of the said gripper members, and means for changing the dwell of the gripper bite on the sheet.

16. In a sheet registering mechanism for sheet fed printing presses, sheet feeding means, a front stop for end registering and temporarily arresting the fed-in sheet, a side guide including a reciprocating side gripper having upper and lower sheet embracing members with coacting sheet gripping surfaces and a stationary side stop located permanently between the sheet gripper surfaces of said gripper members, means for causing the gripper members to grasp the temporarily arrested sheet with a predetermined pressure and pull it laterally into register with the side stop before they reach the end of their stroke and to remain in frictional contact with the sheet during the remainder of the stroke of the said gripper members, and means for opening the grippers after they have completed their said stroke.
